(57) **CLAIM**

The ornamental design for a squeegee, as shown and described.

DESCRIPTION

FIG. 1 is an isometric view of a squeegee;
FIG. 2 is a front view of the squeegee;
FIG. 3 is a rear view of the squeegee;
FIG. 4 is a top side view of the squeegee;
FIG. 5 is a bottom side view of the squeegee;
FIG. 6 is a side view of the squeegee; and,
FIG. 7 is a side view of the squeegee that is opposite the side view illustrated in FIG. 6.
The broken lines depict features of the squeegee that form no part of the claimed design.
